DOOR LOCKING MECHANISM

William F. Wagner, Los Angeles, and Charles E. Cowdery, West Los Angeles, Calif., assignors to Northrop Aircraft, Inc., Hawthorne, Calif., a corporation of California

Application October 22, 1954, Serial No. 463,981

7 Claims. (Cl. 292—341.17)

This invention relates to spring action latches and more particularly to a spring latch adapted to secure and support heavy downwardly swinging horizontal doors.

One object of our invention is to provide a latch for holding and quickly releasing a jettison door in aircraft and other vehicles.

Another object of our invention is the provision of a spring latch that is adaptable to inspection plates, doors, windows, and closures of all kinds regardless of position in which they are mounted.

Another object of our invention is the provision of a latch mechanism adaptable for use with various objects, such as bombs, fuel tanks, stores, cells, rockets, landing gears, engines and the like, to render them releasable from their points of attachment through means operated at positions of remote control.

Another object of our invention is to provide a latch of this type capable of supporting substantial weights and withstanding strong negative external pressures, yet substantially frictionless in operation regardless of the amount of tension involved.

Another object of our invention is the provision of a locking mechanism incorporating automatic means for properly positioning a keeper previous to engagement with a driving pawl.

A further object of our invention is the provision of a locking mechanism having a minimum of parts.

In brief our invention comprises a load bearing latching mechanism including a rotatable disc, having disposed around the circumferential periphery thereof a plurality of outwardly extending claw-like lobes spaced apart by sockets adapted to receive either one of two identical rollers, one being a strike member and attached to the door or closure structure, the other being adapted to prevent reverse rotation of the disc and attached to a spring loaded pawl arm.

Closing of the door causes the strike roller to bear against one of the lobes of the keeper disc, thereby rotating the keeper disc and engaging the strike roller in the adjacent socket.

Simultaneously, rotation of the keeper disc causes the normally engaged pawl roller to move outwardly of one socket and into the next, thereby locking the strike roller and the door in closed attachment. A pivoted lever arm, adapted for operation from a remote point of control, is fitted with an angular projection which, when the lever arm is moved, presses the pawl roller out of socketal engagement thus permitting the keeper disc to rotate backwardly and thereby ejecting the strike roller from socketal engagement and unlocking the door.

Additional objects of our invention will become apparent from the following description of one preferred embodiment of the latching mechanism which is illustrated diagrammatically in the accompanying drawings wherein:

Figure 1 is a perspective underwing view of the forward section of an airplane;

Figure 2 is a sectional side view of the lock mechanism, on the line 2—2 in Figure 3.

2

Figure 3 is a cross sectional view taken on the line 3—3 in Figure 2.

Reference is again made to Figure 1 which shows diagrammatically the forward underbody of a transport aircraft 1 as seen from beneath with the right wing 2 in the upper foreground, with passenger and cargo area 3 in the fuselage 4. Beneath the wing 2 is a longitudinally disposed lateral extension of the fuselage 4 comprising an engine compartment 5 to which access is provided by two doors 6 and 7 having hinge lines paralleling the longitudinal axis of the aircraft and being equipped with remote release latches of the type covered by this application, positioned respectively as indicated at points 6a and 6b, and 7a and 7b.

A third door 8 with latch members 8a and 8b is centrally disposed in the underside of the fuselage and, being hinged along the forward spanwise side of the opening, swings downwardly through an axiodiamic arc of movement. This is the type of door best suited for cargo loading from ground vehicles and for jettisoning cargo and other objects during flight.

Attached to the under side of the wing 2 is a droppable fuel cell 9 which is secured to a wing attachment plate 10 by means of slidably engaging offset brackets at the forward end and, centered in the rearward edge, a load bearing lock of the type described herein fitted with a remote actuation releasing control.

The few different methods of application of these locks are shown merely to suggest a variety of other purposes which it may be used to serve, and the limited number shown herein is not intended to limit the scope of our invention in any degree.

The latch mechanism itself, as seen in Figures 2 and 3, is enclosed in a U-shaped assembly case, which also serves as a mounting bracket, comprising a basal section 21 having parallel sidewalls 21a and 21b disposed perpendicularly to the base making the assembly well adapted for mounting in a recess in the main structure along the edge of the door opening spaced from the hinge line. A transverse shaft 22 is mounted between the sidewalls 21a and 21b on which operating lever arm 23 is adapted to rotate when actuating member 24 is placed under tension.

Unlike conventional bolt type latches and locks, the striker member in the lock of our invention is affixed to the door and the keeper member which is attached to the fixed structure performs the movements required in the locking and releasing operations. In our mechanism the keeper which takes the place of the conventional movable latch bolt is actually a thick disc 25 adapted to rotate freely on shaft 22 and having a plurality of claw-like teeth or lobes 26 extending outwardly from its circumferential periphery interspaced by concave sockets 27 which terminate inwardly in semicircular wall sections 28 dimensioned and conformed to fit snugly around movable roller detents in the manner illustrated at 29. The rollers 30 and 50 are interconnected to pawl arm 35 and door 8 respectively. These rollers restrain or cause to move keeper disc 25.

Roller detent 30, best seen in Figure 2, is adapted to rotate on stud 31 affixed to lower end of pawl arm 35 which in turn is pivoted on transverse shaft 32 supported by sidewalls 21a and 21b. The upper end of pawl arm 35, spaced from detent 30 is terminated in a yoke 33. The upwardly extended sides of yoke 33 have attachment straps 37a and 37b thereon. These pair of straps extend outwardly in parallel alignment from pressure cylinder 38, are pivoted and retained on the yoke 33 by means of studs 36a and 36b. As a result of the described structural arrangement the center of the yoke section is maintained open for lineal movement therethrough of piston rod 39 extending from piston 39p and pivotally attached to operating lever 23 at point 23x. Operating lever 23 is

journalled on transverse shaft 22 and rotates thereon when actuating member 24, attached adjacent the end of the lever spaced from the journal point, is placed under tension at some distant control point by means of a suitable knob, lever, pedal or similar tensioning means.

At the journal end of the operating lever a projection 23p extending diagonally therefrom is provided with a cam surface 23c which when lever is resting against the stop 21s, is disposed contiguously to roller detent 30 and at an angle substantially normal to the arc of movement of detent 30 when rotating about pivot 32.

A helical compression spring 38s is disposed within the cylinder 38 and serves to exert equal and co-reactive pressure upon both of the detent rollers. Outward pressure of spring 38s, transmitted through piston rod 39, holds the lever 23 against stop 21s attached to sidewall 21a when operating lever 23 is not under tension imposed by actuating member 24.

Roller 50 is of substantially the same length and diameter as pawl detent 30, and is adapted to rotate upon a transverse shaft 51 which is supported at each end by the sides of a generally rectangular, rigid, and hollow enclosure or support bracket 56, Figure 2, having a basal end member 52, parallel and generally rectangular side panels 53 and 54 and back panel 55, with the top and front sections being open above and below the strike roller 50 to receive the portions of the keeper disc lobes extending outwardly of the door frame into the opening occupied by the door when closed.

In most cases, and particularly in the aircraft door embodiment being described herein, the support bracket 56 just described, would be built in as an integral part of the door structure and its design specifications would be predicated upon the weight of the door itself, the internal and external pressures to be encountered, and the dead weight of cargo or other objects to be supported by the closure. Rollers 50 and 30 are disposed equidistant from the axis 22 of the keeper disc 25 and substantially in the same horizontal plane.

Operation of the latching mechanism is simple and automatic. Closing the door as at 8A in Figure 2, causes the strike roller 50 to enter a downwardly disposed interlobular socket 27 in keeper disc 25 as shown in phantom at 50A, thereby rotating the keeper disc counterclockwise and simultaneously forcing the pawl detent roller 30 out of the socket as at 30A which it occupied while the door was open. During the final movement induced by closing the door, the keeper disc 25 revolves to a position wherein the outer lobe 26 of the socket in which the strike roller 50 is engaged has rotated counterclockwise and upwardly relative to the strike roller so as to prevent retraction thereof from engagement within the socket 27 without reversing the rotation of the keeper disc. Backward rotation of the keeper disc 25 is prevented, however, by the spring induced movement of the pawl roller 30 into another disc socket 29 newly indexed by the rotation of the disc into the position diametrically opposite from the socket 27 occupied by the strike roller.

When bottomed in this socket 29 the pawl roller 30 is in an over-center position with respect to the wall of the socket bearing against it, while the cam surface 23c, is a positive stop to movement of roller 30 inwardly of this position, and transmits any pressure therefrom through the lever body 23 to the transverse shaft 22 on which it is journalled and to the stop 21s by which it is restrained from further rotation, and thence through the mounting bracket assembly 21, 21a and 21b, to the main structure 4.

The releasing operation is quick and positive, and the movement of associated parts within the mechanism is concurrent rather than sequential. When actuating member 24 is placed under tension at some point of remote control within the main structure, operating lever 23 rotates counterclockwise about pivot point 22 and the cam surface 23c diagonally disposed along the outer edge of lever projection 23p bears against roller detent 30 forcing

it out of engagement within keeper disc socket 29 and causes the keeper disc 25 to rotate clockwise under the weight of the door sustained by the roller 50 which is engaged in a socket in the disc. Clockwise movement of the disc moves engagement lobe 26 downwardly permitting strike roller 50 to swing downwardly out of disc socket 27 when the socket reaches the position indicated as 27A in Figure 2, thereby releasing the door.

Co-reactive spring loading effective upon and equalized between the pawl arm and the operating lever by spring 38s in cylinder 38 causes all of the mechanical elements to return to initial position when roller strike 50 is released and tension on actuating member 24 is relaxed, from their positions of displacement 35A, 23A and 38A respectively to their substantially unintended normal positions of repose.

The final step in the operative cycle is completed automatically when the pawl roller 30 returns to a position of engagement within one of the interlobular sockets of the keeper disc and thereby indexes another of the keeper disc sockets to the diagonally downwardly and outwardly disposed strike-receiving position.

The foregoing description and the accompanying drawings clearly disclose one preferred embodiment of our invention but it will be understood that this disclosure showing the mechanism adapted to an aircraft door is purely illustrative of only one of the many use applications in which it may be employed; and that such changes in the invention may be made as are fairly within the scope of the following claims:

What is claimed is:

1. A door latch mechanism comprising a rotatable disc journalled to stationary structure along an inner edge of a door frame therein; said disc having disposed about the edgewise circumferential periphery thereof a plurality of outwardly extending claw-like lobes spaced apart by concave sockets; a longitudinally extended pawl member pivoted intermediate its length to the main structure; detent member mounted on said pawl member and adapted for engagement in one of said sockets of said disc to prevent backward rotation thereof; spring loading means for maintaining the positioning of the associated mechanical components; camming means for disengaging said pawl detent from said disc socket to permit backward rotation of said disc; a lever arm journalled coaxially with and adjacent to said disc; an actuating member attached to the end thereof spaced from said journalled end; a projection from one side of said lever arm adjacent said journal end; said projection having an outwardly extended smooth edge diagonally disposed adjacent said pawl detent, said smooth edge being effective as a cam surface to bear against said detent and disengage it from said disc socket when said lever arm is rotated by said actuating means.

2. Apparatus in accordance with claim 1 wherein said spring loading means comprise: a helically coiled spring disposed within a longitudinally extended cylinder; said cylinder being pivotally attached at the open end thereof to the outer end of said pawl arm spaced from said pawl detent roller; a piston slideable within said cylinder and entered through the open end thereof, said piston having a rod extending outwardly therefrom and pivotally attached to said lever arm adjacent the end spaced from said journalled end thereof, whereby said coil spring is compressible between the bottom of said cylinder and said piston upon movement of said pawl detent and lever arm toward each other.

3. Apparatus as set forth in claim 2, and additionally thereto, means adapting the spring tension for easy movement during the single action latching operating cycle of the mechanism, comprising: a stop member, fixedly attached to stationary structure adjacent the outwardly extended end of said operating lever and spaced from the journal end thereof; said fixed stop being adapted to arrest rotation of said lever at the position wherein

said cam surface is disposed contiguous to but not bearing against said pawl detent, whereby said lever remains immobile when the disc is rotated counterclockwise upon closing of said door, thus limiting the generating of spring compression to that imposed by the movement of said pawl detent outwardly from one of said disc sockets and into the next.

4. In a lock mechanism having a rotary disc member, a pawl arm and detent to arrest rotation of said disc, a lever arm to release said disc member and spring loading means for maintaining positioning of components during periods of immobility as set forth in claim 2 and, additionally thereto, spring tension attaching means comprising: a longitudinally extended cylinder, closed at one end and adapted to receive a piston and piston rod through the open end for slideable longitudinal movement therein; two attachment straps disposed diametrically opposite an outer surface of said cylinder adjacent said open end thereof; a yoke structure fixedly attached to the outwardly extended end of said pawl arm spaced from said pawl detent, the terminal portions of the two spaced members of said yoke structure being pivotally attached to two attachment straps oppositely attached to the periphery of said cylinder and said piston rod movable transversely between said pivotal attachments of said yoke ends and said cylinder attachment plates upon changes in spacing of said operating lever and said pawl arm.

5. A load bearing door latching mechanism comprising: a rotatable keeper disc, journaled to stationary structure along the inner face of the door frame therein, and having a plurality of evenly spaced outwardly extending claw-like lobes disposed about the circumferential periphery thereof, said lobes being interspaced by concave sockets semicircularly conformed at the innermost terminations thereof adjacent the axis of said disc; a pawl arm pivoted to said stationary structure, and having at one end a stud member fixedly attached thereto, said stud member being disposed in axial alignment with said disc and having mounted thereon a roller member adapted for snug engagement within a disc socket whereby backward rotation of said disc is prevented.

6. A load bearing latching mechanism including the components and the relative positioning thereof as set

forth in claim 5 together with additional means for absorbing stresses created by the weight of the door, comprising: journaling said operating lever coaxially with said rotary disc, providing the outwardly extended portion of said lever with a solid stop affixed to the main structure and adapted to arrest the clockwise movement of said lever at a point at which said cam surface, diagonally disposed along the edge of said lever, is contiguous to said pawl detent when said detent is seated in locked engagement within one of said sockets of said rotary disc and is positioned normal to the arc of rotation of said disc sockets at the over-center point at which said arc of rotation is intersected by the arc of rotation of said pawl detent, whereby said thrust force tending to rotate said disc into tighter binding engagement with said pawl member is transferred by said pawl member to said cam surface and thence through said lever journal and stop to said main structure.

7. A closure latch mechanism for structure comprising a body mounted on said structure; a shaft supported by said body; a ratchet wheel freely rotatable on said shaft; an elongated, spring loaded pawl cam pivotal on said shaft; a stop on said structure and overlying said roller detent against which said spring loaded pawl cam is engaged; a spring loaded lever pivotally mounted in said body; a roller detent on said lever, that is in linear alignment with said shaft and is received between the teeth of said ratchet when the closure is opened and closed; and means on said pawl cam for urging 30 said cam from the stop engaging position.
